UNITED STATES PATENT OFFICE.

GEORGE W. HOOK AND OSCAR C. HOOK, OF BROOKLANDVILLE, MARYLAND.

LOCK.

1,187,837.

Specification of Letters Patent. Patented June 20, 1916.

Application filed April 8, 1914. Serial No. 830,523.

To all whom it may concern:

Be it known that we, GEORGE W. HOOK and OSCAR C. HOOK, citizens of the United States, residing at Brooklandville, in the 5 county of Baltimore and State of Maryland, have invented certain new and useful Improvements in Locks, of which the following is a specification.

The object of this invention is to provide 10 a lock of the permutation type having a case provided with a recess on the face thereof with a door to cover the recess, the bolt being mounted to be normally held in its locked position, and means being provided to move the bolt from the locked position 15 when the permutation disks have been brought to the proper setting in which the notches or slots thereof are in registry.

A further object is in the provision of a 20 connection between the cover for the recess portion of the case, and the means by which the bolt is moved to the inoperative relation, so arranged that as the cover is given movement in a predetermined relation the 25 means to move the bolt will become operative.

With other objects in view, which will be referred to, our invention consists in the 30 peculiar combination and novel arrangement of parts, such as will be hereinafter more fully described in connection with the accompanying drawing and more particularly pointed out in the appended claims.

In the drawing:—Figure 1 is a view in 35 side elevation of a padlock showing our improvement applied thereto. Fig. 2 is a view similar to Fig. 1 with the case of the padlock in section to illustrate the interior arrangement of the parts. Fig. 3 is a vertical transverse sectional view on the line 3—3 of Fig. 2. Fig. 4 is a similar view on the line 4—4. Fig. 5 is a horizontal transverse sectional view on the line 5—5 of Fig. 2. Fig. 6 is a view in side elevation of a 45 lock of the trunk or chest type showing our invention applied thereto. Fig. 7 is a view similar to Fig. 6 showing parts in section to more clearly illustrate the manner of applying our invention to this form of lock. Fig. 8 is a horizontal transverse sectional view through the lock shown in Figs. 6 and 50 7. Fig. 9 is a view in side elevation and in partial section to disclose an adaptation of our invention to a lock of the type used on 55 a swinging door. Fig. 10 is a fragmentary

detail view to better illustrate the parts shown in Fig. 9.

Referring to the structure disclosed in Figs. 1 to 5 inclusive, the body 1 and the shackle 2 are of the form usually adapted to padlocks, the shackle being pivoted in the usual manner at 3 to the body and the body provided at the opposite side with an opening 4 to which the latch end 5 of the shackle may be inserted.

A slide bolt 6 is mounted within the body 1 in a position that it may be brought into engagement with the slot 7 of the latch end 60 of the shackle 2. The bolt 6 is mounted to have endwise sliding movement into and out 70 of its engagement with the locked end of the shackle 2. A bolt lever 8 is pivoted at 9 within the casing or body 1 of the lock and the bolt 6 is connected with one end of this bolt lever 8 to have sliding and pivotal 75 movement by a pin 10 carried by the lever 8 passing through a slot 11 formed in the bolt 6. Springs 12 are secured to the pin 9 on which the bolt lever 8 is pivoted and at their free ends bear against the rear end 80 of the bolt 6 to hold the bolt normally in a position shown in Fig. 2, the bolt lever 8 being at the same time moved around its pivot 9 by the engagement of the pin 10 with one end of the slot 11.

Adjacent the free end of the bolt lever 8 the permutation disks 13 and 14 are mounted to have turning movement and to have 85 their axes of rotation in the direction of the transverse extent of the body 1 of the lock. The disk 13 is secured on the pin 15 which extends through one side of the body of the lock and on its outer end has an indicating or dial wheel 16 secured. The disk 14 is carried by a sleeve 17 mounted to turn 90 on the pin 15 and on the outer end of this sleeve an indicating wheel 18 is secured to lie between the side of the body 1 of the lock and the indicating wheel 16 secured on the pin 15. By arranging the parts in this 95 manner the permutation disks 13 and 14 can be revolved in either direction and may be revolved independently one of the other. The disks 13 and 14 are provided around their peripheries with a plurality of comparatively shallow transverse slots 19 and 20, respectively. The disk 13 has a slot 21 100 formed in its periphery of a greater depth than the slot 19, and disk 14 has a similar slot 22.

110

The bolt lever 8 has on its free end an arm 23 which extends in the direction of the permutation disks 13 and 14 and comes into close proximity therewith when the parts 5 are in the relation shown in Fig. 2 in which the bolt is in its locking position. A releasing arm 24 is mounted pivotally on a pin 25 within the casing to engage with the free end of the bolt lever 8 and this releasing 10 arm has a thumb piece 26 connected therewith to extend through an opening 27 formed through the body 1 of the padlock so that it can be operated from the exterior.

15 The operation of the lock is as follows: When the padlock is closed or locked the parts occupy the relative position disclosed in Fig. 2, the bolt 6 is held in its locking position in the notch 7 by the springs 12 bearing against the rear end thereof, the 20 bolt lever is held at a position that the arm 23 is out of engagement with the disks 13 and 14 by reason of its connection with the bolt 6 and the releasing arm 24 is held in the position shown by the engagement of the 25 bolt lever therewith. With the parts in the relation shown, the thumb piece 26 may be depressed thus swinging the releasing arm 24 around its pivot and throwing the 30 bolt lever around its pivot on the pin 9 toward the permutation disks 13 and 14, the arm 23 of the lever 8 will be brought into engagement with these disks and may pass into the slots 19 and 20, however, this movement of the bolt lever and the consequent 35 movement of the bolt 6 through its connection by the pin 10 is not sufficiently great to withdraw the bolt 6 from the notch 7 of the latch end 5 of the bolt of the padlock, and consequently the bolt is not released. By turning the dial wheels 16 and 18 so that they indicate a predetermined point, the 40 slots 21 and 22 of the disks 13 and 14 may be brought into registry and into the path 45 of the arm 23. With the parts in this relation pressure upon the thumb piece 26 will throw the releasing lever around its pivot against the bolt lever 8 and will cause the arm 23 thereon to be moved into the slots 50 21 and 22 which permit greater swinging movement of this bolt lever about the pin 9 and withdraw the bolt 6 from the slot 7 thus releasing the shackle 2 from its locked 55 position.

60 When the turning force is released from the thumb piece 26 the springs 12 will again slide the bolt 6 to its outward position and the bolt lever and the releasing arm will be moved back to their normal positions, the disks 13 and 14 may then be turned from the predetermined position to which they have been moved and it is not now possible to swing the bolt lever to its full extent around the pivot pin 9, in fact, the bolt with 65 the parts in this relation cannot be moved

to a point with its locking end beyond the extent of the opening 4 through which the latch end of the shackle 2 is passed. This protrusion of the bolt 6 within the opening 4 does not however, prevent the closing and locking of the shackle 2. When this bolt is closed the latch end 5 engages against the end of the bolt 6. The endwise pressure thus exerted causes the bolt 6 to be moved back against the tension of the springs 12 and this movement with relation to the bolt lever is permitted by the pin carried thereon passing through the slot 11 of the bolt.

70 With the form of lock shown in Figs. 6, 7 and 8, the case is made of a slightly different design, it being square or substantially so and adapted to be rabbeted into the upper edge of a trunk or chest. A catch 28, which in its form and application is substantially the same as the latch end 5 of the shackle 2 of the prior disclosure, is secured to the top or other part to be brought down and held in a locked position. The front plate 29 of the case 30 of this lock is recessed with respect to the outer face of the structure to which it is attached and a cover plate 31 is pivoted on a pin 32 to be swung to a position to close over this recessed portion and is held in its closed position by a lock 33 which is made in the 75 form of a turn button. The pin 32 which is pivoted to the casing and to which the cover plate 31 is secured extends through the casing at a point corresponding with the location of the pin 25 in the disclosure 80 in Fig. 2 and this pin 32 has a releasing arm 34 secured thereon to perform the same function as the releasing arm 24 in the disclosure of the padlock. To release this lock from its operative position the cover plate 31 is swung, as shown in Fig. 6, to uncover the recessed portion, the indicating wheels are then turned to a position that the slots 85 in the permutation disks register and are in a relation to receive the arm on the bolt lever. The cover plate 31 is then given a further downward swinging movement which causes the releasing arm 34 to bear 90 against the bolt lever and withdraw the bolt from the catch 28.

95 In the disclosure in Figs. 9 and 10, the casing of the lock is substantially the same as in Figs. 6, 7 and 8, and in this connection is adapted to be connected by rabbeting or otherwise to one of the side edges of a 100 swinging door. The bolt 35 has the end beveled as at 36 and the member with respect to which the door is to be secured carries the socket 37 in position to receive this beveled end of the bolt 35. Another slight modification is that a hand wheel 40 is provided to turn the releasing arm to a position that it withdraws the bolt from its 105 operative position.

110 From the foregoing, it will be seen that 115

we have provided a lock structure of the permutation type so designed that it may be adapted to any of the forms of lock now in common use and one which while very simply and cheaply manufactured is yet very efficient in operation.

While we have herein shown and described only specific forms of our invention, it will be understood that slight changes might be made in the form and arrangement of the parts to suit the particular adaptation without departing from the spirit and scope of our invention, and hence we do not wish to be limited thereto except for such limitations as the claims may import.

We claim:—

1. A lock as described comprising a bolt, a bolt lever pivoted at its center at a point adjacent the bolt and flexibly connected at one end therewith in such a manner that upon rocking of the lever the bolt is withdrawn from its locked position, springs connected at the point of pivot of said bolt lever to exert resilient action against said bolt to normally hold the same in the thrown position and to move the bolt lever about its central pivot, a plurality of permutation disks mounted to turn adjacent the free end of the bolt lever and to normally preclude rocking movement thereof, each of said disks provided with a slot, means to turn said disks to a position that the slots register to permit rocking movement of the bolt lever, and means arranged to be manually moved into engagement with the free end of the bolt lever to rock the same against the tension of said springs and to release the bolt from the locked position.
2. A lock comprising a bolt, a bolt lever pivotally mounted at its center and at its one end provided with an inturned arm, a flexible connection between the remaining end of said bolt lever and the bolt arranged in a manner that upon rocking of the bolt lever the bolt is moved to an inoperative position, springs connected rigidly at the point of pivot of said bolt lever to have their free ends engage with the bolt to normally hold the same in the thrown position and to rock said bolt lever about its center, a plurality of permutation disks mounted to turn adjacent the free end of the bolt lever and to normally form an obstruction to the moving of said bolt lever through engagement of the arm therewith to preclude locking movement of said lever, each of said disks provided with a slot, means to turn said disks to a position that the slots register to permit entrance of the arm, and manually operable means to be engaged with the free end of said lever to cause movement of the arms within the confines of the slots against

the tension of said spring and to thus withdraw the bolt from the locked relation. 65

3. A lock comprising a casing having a recessed face, a cover plate for said recessed portion mounted to permit movement to open and close the same, locking means within the casing, lock operating means located within said recessed portion to be accessible when the cover is opened, and means connected with said cover plate to become operative upon movement of said plate to pass the full open position subsequent to the setting of the lock operating means to release the same. 70 75

4. A lock comprising a casing recessed on its face, a cover plate for said recessed portion mounted to be capable of movement to the open and closed positions, a bolt within the casing, a plurality of permutation disks mounted to turn adjacent the bolt and to normally preclude movement of the bolt from its locked position, each of said disks provided with a slot, means to turn said disks to a position that the slots register, and means operated by the cover to move the bolt from the locked relation. 80 85

5. A lock comprising a casing recessed on its face, a cover plate for said recessed portion, a hinge pin by which said cover is mounted to permit opening and closing of the same, a bolt within the casing, means to hold the bolt in a locked relation, means to release said bolt-holding means, and means connected with the pin to throw the bolt to the unlocked position when the parts are set in the released position and the cover plate is given continued movement in the direction of opening the same. 90 95 100

6. A lock comprising a case recessed on its face, a cover for said recessed portion secured to a pin pivotally mounted in said case and adapted to be turned to a position that the cover is swung from its closed position, a bolt within the casing, a plurality of permutation disks mounted to turn adjacent the bolt and to normally preclude movement of the bolt from its locked position, each of said disks provided with a slot, means to turn said disks to a position that the slots register, and means connected with said pin to be operable upon continued swinging movement of the cover beyond the full open position and when the slots are in registry to withdraw the bolt from its locked position. 105 110 115

In testimony whereof we affix our signatures in presence of two witnesses.
